[57] CLAIM

The design for the umbrella case backpack, as shown and described.

DESCRIPTION

FIG. 1 is a top plan view of the umbrella case backpack showing my new design;

FIG. 2 is a right side elevational view thereof;

FIG. 3 is a front elevational view thereof;

FIG. 4 is a rear elevational view thereof;

FIG. 5 is a left side elevational view thereof;

FIG. 6 is a bottom plan view thereof;

FIG. 7 is a top, rear, right side perspective view with the straps broken away for clarity;

FIG. 8 is a top, rear, right side perspective view of a second embodiment, with the straps shown broken away for clarity;

FIG. 9 is a top, rear, right side perspective view of a third embodiment, with the straps shown broken away for clarity; and,

FIG. 10 is a top, rear, right side perspective view of a fourth embodiment, with the straps shown broken away for clarity; Embodiments 2-4 are identical to embodiment 1, with the exception of the alternate strap and alternate closure means.
